UNITED STATES PATENT OFFICE.

SPENCER C. CARY, OF BALDWIN, NEW YORK.

DESIGN FOR A BOX-FASTENER.

SPECIFICATION forming part of Design No. 28,142, dated January 11, 1898.

Application filed October 15, 1894. Serial No. 526,993. Term of patent 14 years.

To all whom it may concern:

Be it known that I, SPENCER C. CARY, a citizen of the United States of America, and a resident of Baldwin, Queens county, New York, have invented and produced a certain new, useful, and original Design for a Box-Fastener, of which the following is a specification, reference being had to the accompanying drawings, forming part of the same, in which—

10 Figure 1 is a plan view of a box-fastener formed in my new design. Fig. 2 is an edge-wise view of the same.

The design consists, primarily, in a box-fastener having ends bounded by curved 15 lines and upwardly or downwardly extending prongs, with openings in the material, the main surface of which is plain, and the essential features are a plain flat body bounded at

the sides by substantially straight lines and at each end by a curved line having near 20 each end openings in the face and prongs extending from the sides of the openings at substantially right angles to the surface of the main body of the fastener.

What I claim as my invention, and desire 25 to secure by Letters Patent, is—

The design for a box-fastener substantially as herein shown and described.

In testimony that I claim the foregoing as my invention I have signed my name, in presence of two witnesses, this 13th day of October, 1894.

SPENCER C. CARY.

Witnesses:

A. G. N. VERMILYA,
A. T. FALES.
